UNITED STATES PATENT OFFICE.

JOSEPH BERGER, JR., OF UTICA, NEW YORK, ASSIGNOR TO UNION SPECIAL MACHINE COMPANY, OF CHICAGO, ILLINOIS, A CORPORATION OF ILLINOIS.

THROAT-PLATE FOR SEWING-MACHINES.

1,283,639.

Specification of Letters Patent.

Patented Nov. 5, 1918.

Application filed December 30, 1916. Serial No. 139,824.

To all whom it may concern:

Be it known that I, JOSEPH BERGER, Jr., a citizen of the United States, residing at Utica, in the county of Oneida, State of New York, have invented certain new and useful Improvements in Throat-Plates for Sewing-Machines, of which the following is a description, reference being had to the accompanying drawing and to the figures 10 of reference marked thereon.

The invention relates to new and useful improvements in throat plates for sewing machines, and more particularly to a throat plate for a multiple needle stitching mechanism which is adapted to unite overlapped edges of fabric sections and cover the trimmed edges of the fabric sections.

An object of the invention is to provide a throat plate which is formed with means 20 for guiding fabric sections with their edge portions upturned for trimming, and means coöperating with the presser foot in overlapping the edges after they are trimmed and before they cross the needle openings 25 in the throat plate, so that the trimmed edges may be overlapped and covered and joined by the stitching mechanism.

In the drawings, which show by way of illustration one embodiment of the invention,—

Figure 1 is a plan view of a portion of a work support having a throat plate embodying my improvements;

Fig. 2 is a plan view showing certain 35 parts of a sewing machine which coöperate with the throat plate;

Fig. 3 is a sectional view through the presser foot, and throat plate, also showing the position of the needles, the section being 40 taken in front of the trimmers;

Fig. 4 is a similar sectional view through the presser foot and throat plate, the section being taken in rear of the trimmers;

Fig. 5 is a similar sectional view substantially at the stitching point; and

Fig. 6 is a longitudinal sectional view through the throat plate.

My improved throat plate is especially adapted to be used in connection with

the joining of overlapped fabric sections 50 wherein the fabric sections have their edge portions upturned and directed to a horizontal trimming mechanism where the edge portions are trimmed and prepared for uniting, after which one of the edge portions is 55 turned underneath the other, and the last-named edge portion is then turned down onto the first-named edge portion so that the fabric sections overlap, and said overlapped portions are joined and covered by suitable 60 stitching mechanism. The present invention is directed particularly to the throat plate which is so constructed as to aid in the directing of the upturned portions to the trimming mechanism and to assist in the 65 overlapping of said edge portions.

Referring more in detail to the drawings, my improved throat plate is indicated in the drawings at 1, and said throat plate is adapted to be secured to the work support 70 2 by suitable screws 3, which pass through openings in the throat plate. The throat plate is formed with the usual feed slots which are indicated at 4. Said throat plate is also provided with needle openings, which 75 are indicated at 5, 6 and 7. There is a stitch tongue between the needle openings 5 and 6, and also a stitch tongue between the needle openings 6 and 7.

Directly in front of the needle openings 80 there is an inverted V-shaped rib 8, which extends from the front end of the throat plate longitudinally of the throat plate and terminates directly in front of the needle openings. This inverted V-shaped rib is cut away as at 9, in order to form a space for the turning down of one of the trimmed edge portions, as will be described more in detail hereinafter. The throat plate is also formed with a depressed section 10 at one 90 side of said rib 8. Coöoperating with the throat plate is a presser foot indicated at 11 in the drawings, and this presser foot has a slot 12 which extends rearwardly from the front edge of the foot and terminates 95 directly in front of the needle openings in the presser foot. This slot registers with the rib 8.

The fabric sections to be united are indicated in the drawings at F and F'. The edge portions f and f' are turned up out of the plane of the fabric sections and directed 5 along the inclined sides of the rib 8. This rib serves to hold the sections upturned, and directs them between the trimming blades, which are indicated at 13 and 14. The trimming blades operate to trim the 10 upturned portions. The cut away portion 9 begins just in front of the trimming point, so that the edge portion f' after having passed the trimming blades is relieved of the support due to the rib 8 and a projecting 15 guide on the presser foot indicated at 15 (see Fig. 4) operates to crowd this edge portion f down into the cut away section, while the other wall of the rib 8 serves to hold the edge portion f' raised, and permits 20 the turning of the edge portion f underneath the same. The rib terminates in advance of the needles, so that the sections may be brought back into the plane of the fabric sections, as indicated in Fig. 5, where the 25 fabric sections are shown as overlapped.

The needles are indicated at 16, 17 and 18 in the drawings, and these needles are so disposed relative to the overlapped fabric sections that the center needle 17 passes 30 through the overlapped portions, while the needle 16 enters the fabric section F only and the needle 8 enters the fabric section F' only. This insures that the trimmed edges will be covered by the stitching, as well as 35 the fabric sections joined by the stitches which extend through the same.

The throat plate, as above noted, has a depressed portion 10, so that the surface 19 of the said depressed section is lower than 40 the surface 20 on the other side of the rib 8 which results in the supporting of the fabric section F' in a plane slightly higher than the fabric section F and facilitates the turning of the edge portion of the fabric F' underneath the edge portion of the fabric section F, as clearly shown in Figs. 3 and 4 of the drawings. The presser foot is formed with an enlarged portion 21 which holds the fabric on this depressed part of the throat 50 plate.

From the above, it will be apparent that my improved throat plate includes an inverted V-shaped rib which supports the upturned edge portions of fabric sections 55 which are to be trimmed, and this rib is cut away so as to allow one of the edge portions to be turned underneath the other after it is trimmed and before it reaches the stitching mechanism. The throat plate is also formed 60 with a depressed section which allows one of said fabric sections to be fed in, in a plane slightly lower than the other fabric section, and this in turn enables the fabric sections to be more readily overlapped.

The rib 8 is substantially parallel with 65 the line of feed and is located slightly at one side of the center needle, so that although the section F of the fabric is turned up to a greater extent than the section F', when these upturned portions are brought 70 back into the plane of the fabric sections they will overlap each other to a uniform extent, relative to the outer needles, and lie close to the path of travel of said outer needles.

It is obvious that minor changes in the details of construction and the arrangement of parts may be made, without departing from the spirit of this invention, as set forth 75 in the appended claims.

Having thus described the invention, what is claimed as new is:—

1. A throat plate for sewing machines having needle-openings therein, and an inverted V-shaped rib located in front of said 85 needle openings for supporting the upturned edge portions of fabric sections which are to be trimmed, said rib being cut away on one side thereof between the trimming point and the needle openings, so as to permit one 90 of the edge portions to be turned underneath the other.

2. A throat plate for sewing machines having needle openings, an inverted V-shaped rib carried by the throat plate and 95 located in front of said needle openings for guiding the upturned edge portions of fabric sections to be trimmed, said rib being disposed in a line parallel with the line of feed, the surface of the throat plate at one 100 side of said rib being lower than the other to facilitate the overlapping of the upturned edges after they are trimmed.

3. A throat plate for sewing machines having needle openings, an inverted V- 105 shaped rib carried by the throat plate and located in front of said needle openings for guiding the upturned edge portions of fabric sections to be trimmed, said rib being disposed in a line parallel with the line of feed, the surface of the throat plate at one 110 side of said rib being lower than the other to facilitate the overlapping of the upturned edges after they are trimmed, the center line of said rib being located at one side of the 115 center of the needle openings, whereby the fabric sections will be overlapped substantially to the same extent at each side of the center of said needle openings.

4. A throat plate for sewing machines 120 having needle openings, an inverted V-shaped rib carried by the throat plate and located in front of said needle openings for guiding the upturned edge portions of fabric sections to be trimmed, said rib being 125 disposed in a line parallel with the line of feed, the surface of said throat plate at one side of said rib being lower than the other

to facilitate the overlapping of the upturned edges after they are trimmed, said rib being cut-away on the side thereof adjacent the lower surface of the throat plate and between the trimming point and the needle openings so as to facilitate the turning of the edge portion of the fabric section guided on the lower surface of the throat plate un-

derneath the edge portion of the other fabric section.

In testimony whereof, I affix my signature, in the presence of two witnesses.

JOSEPH BERGER, JR.
